Primary Examiner — Cathron C Brooks*Assistant Examiner* — Deanna Fluegeman(74) *Attorney, Agent, or Firm* — Carol N. Green, Esq.(57) **CLAIM**

The ornamental design for card reader device, as shown and described.

DESCRIPTION

FIG. 1 is a top plan view of the card reader device.
 FIG. 2 is a bottom plan view of the card reader device.
 FIG. 3 is a right side elevation view of the card reader device.
 FIG. 4 is a left side elevation view of the card reader device.
 FIG. 5 is a front view of the card reader device.
 FIG. 6 is a rear view of the card reader device.
 FIG. 7 is a top front left perspective view of the card reader device.
 FIG. 8 is a bottom perspective view of the card reader device; and,
 FIG. 9 is a top front right perspective view of the card reader device in use with the card shown in broken line.
 The portions of the card reader device illustrated in broken lines form no part of the claimed design. The broken line showing of the unclaimed card in FIG. 9 is included for the purpose of illustrating the unclaimed environment of the card reader device during use and forms no part of the claimed design.
